UNITED STATES PATENT OFFICE.

ERICK SILEN, OF MAYGER, OREGON.

VIOLIN-PIANO.

1,115,601.

Specification of Letters Patent.

Patented Nov. 3, 1914.

Application filed February 28, 1913. Serial No. 751,330.

To all whom it may concern:

Be it known that I, ERICK SILEN, a citizen of the United States, residing at Mayger, in the county of Columbia and State of Oregon, have invented a new and useful Violin-Piano, of which the following is a specification.

The present invention relates to improvements in violin pianos, the structure herein shown being the refinement of the violin piano as covered by applicant's Patent No. 1,045,899, issued December 3, 1912, the primary object of the present invention being the provision of a piano of this character, 15 in which a novel form of flexible bowing disk is employed, in combination with a rotary and oscillatory means carried by a shaft for actuating the bowing disk to produce a quaver effect or to actuate a hammer 20 for producing a tremolo effect upon the strings of a piano.

A further object of the present invention is the provision of a means whereby the bar, actuated through the keys of the piano 25 mechanism will properly flex the bowing disks and operate the tremolo hammers, may be controlled through the medium of an automatic player.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed, can be made within the scope of what is claimed without departing from the spirit of the invention.

In the drawings—Figure 1 is a front elevation of a violin piano constructed according to and embodying the present invention, a portion of the front panels of the same being broken away to show the construction of the power device and the violin attachment at the right hand corner thereof. Fig. 40 2 is a vertical transverse sectional view through the violin piano on the line 2—2 of Fig. 1. Fig. 3 is an enlarged detail elevation of the bow disk operating mechanism 45 and the tremolo and quaver producing shaft with its operating mechanism. Fig. 4 is a front elevation thereof showing a means for elevating and lowering the tremolo and quaver producing shaft. Fig. 5 is an enlarged detail view showing the mounting of 50 the last mentioned shaft. Fig. 6 is an enlarged diagrammatic perspective view of the

various manually controlled levers for operating the various mechanisms of the violin piano. Fig. 7 is a transverse sectional view 60 on an enlarged scale through the casing for supporting the flexing means for the bowing disks and the resin supplying device, a single bowing disk and one string of the piano being shown in elevation. Fig. 8 is a top 65 plan view thereof showing a plurality of bowing disks and strings with a plurality of the bowing disk flexing devices. Fig. 9 is a front elevation of the mechanism as shown in Fig. 8. Figs. 10 and 11 are enlarged detail views of a single bowing disk. Fig. 12 is an enlarged detail elevation showing a single string and the individual means for producing a quaver effect upon a bowing disk and for operating a tremolo hammer. Fig. 13 is a front elevation of a number of 70 the same. Fig. 14 is an enlarged detail view showing the connection of a single key and one of the damper devices. 75

In describing the present invention, the 80 same will be taken up under the following sub-topics: the cabinet and motor; the bowing disk and mechanism for operating the same; the tremolo and quaver producing devices; the resining device; and the damping device control. 85

The cabinet and motor.—Referring to the drawings. A designates the piano cabinet, having the usual key-board B and the vertically or angularly stretched strings C, said 90 strings being arranged across as usual in front of the sounding board D similarly to the usual construction of piano.

Disposed within the lower portion above the face of the cabinet are two parallel 95 standards, 1, in which is journaled the horizontal shaft 2, one end of said shaft being journaled intermediate of the ends of the taller or vertical standard 1' disposed toward the right hand portion of the cabinet, 100 as shown in Fig. 1. Keyed upon the shaft 2 between the standards 1 is a single drum 3, provided with the two grooves 3' and 3^a there being disposed upon the shaft 2 for oscillation, the two levers 4—4', each one of 105 which carries its weight-actuated groove-engaging pawl 5—5'. The upper end of each of the pawls 5—5' is provided with a hooked terminal 5^a, disposed to engage respectively in the peripheral grooves 3' and 3^a so that 110 as the foot treadles 12—12', through the links 13—13', are operated by the performer, a continuous rotation will be imparted through the drum 3 to the shaft 2. Keyed

upon the shaft 2 is a friction wheel 6, which is in engagement with a small friction wheel 7 disposed upon the short horizontal shaft 8, said horizontal shaft 8 being provided with the two balance or fly wheels 9—9'. Upon the shaft 2 adjacent to the friction wheel 6 are keyed the small grooved pulley 10 and the belt-carrying pulley 11. Disposed to be trained over the grooved pulley 10 is a round belt 14, there being a flat belt 15 trained over the pulley 11, as clearly illustrated in Figs. 1, 2, 3 and 4. A belt tightener 16 is provided.

The belt 14 having a weight actuated tightener 16' is disposed to pass over a guide pulley 17, mounted upon the plate 21 of the frame for supporting the mechanism within the cabinet and about the pulley 18 keyed upon the shaft 19. This shaft as will later appear, is disposed for sliding movement within the slots 20 of the plates 21, there being two or more of these frames disposed throughout the length of the piano. The belt 15, as clearly shown, is crossed and passes over the small pulley 22 disposed upon the bow disk carrying shaft 23, the detail description of both of which will appear later on.

It will thus be seen that as the motor is operated at all times, that both shafts 19 and 23 will also be continuously rotated.

Bowing disk and operating mechanism.—The shaft 23, as clearly shown is disposed longitudinally of and to the front of the respective strings C, the intermediate portion 35 being formed square or in the shape of a rectangle, as clearly shown in Figs. 7 and 10, there being disposed upon the shaft 23 adjacent each string C and in pairs, leather cellars 24—24', between which is mounted 40 the flexible bowing disk 25, said bowing disk 25 being loosely mounted upon the shaft so as to be capable of both a longitudinal sliding movement as well as a tilting movement, as clearly illustrated in full and dotted lines 45 in Fig. 11.

Each of the disks is preferably made of a plurality of nested concaved sections of a suitable flexing material, such for instance as celluloid, and each disk has its outer periphery formed as at 26, to produce a string-engaging portion with a plurality of concentric rims.

The plate 27 is disposed longitudinally of the piano casing and carries the two parallel strips 28, which with the plate 29 form a rectangular boxing, as clearly illustrated in Fig. 7, for the proper journaling of the bow-disk controlling rods 30, there being one rod to each bowing disk. Each rod is provided 60 with the offset portion 31 to provide a means for retaining the same against longitudinal movement within the journaling box so that the upstanding arm 32 will be properly disposed relatively to its bowing disk to engage 65 the outer curved face thereof to flex the disk

to cause the edges 26 thereof to engage the string C. In order to operate the rods 30, each rod is provided with a crank arm 33, which is operably connected to the upper end of the vertically movable bars 35, there being one bar 35 to each rod 30 and consequently one rod 30 to each bowing disk 25. A spring 34 is so disposed upon each rod 30 as to normally maintain the bowing disk engaging end 32 out of engagement with the bowing disk, so that the disk may rotate between the adjacent strings C without contacting the same, it being necessary to flex the disk in order to assume the dotted line position in Fig. 11 to engage its respective string during the rotation of the disk.

In order to properly elevate the bar 35 and thus cause the flexing of the selected bowing disk, the lower end of the bar 35, as clearly illustrated in Fig. 14, is adjustably connected by means of the coupling 36 to the front free end of the short lever 37, said lever 37 being pivoted to a fixed depending flange 38 carried by the longitudinally disposed frame plate 39. A coupling link 40 is connected to the forward free end of the lever 37 and to the rear free end of the key 41, so that the depression of the selected key 41, will elevate the free end of the lever 37, and consequently the bar 35.

Tremolo and quaver producing devices.—The shaft 19 as heretofore described, is rotated simultaneously with the shaft 23, and as will presently appear, controls the tremolo hammers 48 and imparts the necessary movement to the bar 35 to produce a tremolo effect upon the bowing disk.

Keyed upon and rotatable with the shaft 19 is a bar 42, the outer periphery of which as clearly illustrated in Fig. 12 is provided with the concavities 43 and the ridges 44.

Carried by the plate 45 which is disposed longitudinally of the piano cabinet, are a plurality of supports or plates 46, one to each string of the piano, and carried by each plate 46 for resilient swinging movement by the spring 47 is a tremolo hammer 48. The string-engaging head 49 of each hammer 48 is normally in the position, shown in Fig. 12. A resilient support 50 is carried by the hammer 48, and has journaled therein a felt roller 51, which is mounted to be engaged by the periphery of the bar 42 when the bar 42 is lowered. Thus the rotation of the bar 42 will impart a rapid vibratory movement to the hammer 48 to cause the end 49 thereof to engage one string C to produce the desired tremolo effect, this hammering effect upon the string being simultaneously with the engagement of the selected bowing disk therewith.

In order to elevate the outer end of the selected tremolo hammer 48 when the bar 35 is elevated, the structure shown in Figs. 12 and 13 is employed. The apertured screw 130

52 in this instance has connected thereto one terminal of the cord 53, said cord 53 being threaded through the guide arm 54 and connected to the rear face of the bar 35, being adjustably connected to the bar through the medium of the adjusting screw 55.

The quaver effect is produced without affecting the tremolo hammers 48, and through the instrumentality of the levers 59, which as clearly shown, are mounted upon or pivoted to supporting flanges 57. The flanges 57 are secured to the longitudinal plate 56 which is supported from the plate 21 and to the rear of the vertically-slidable bow-disk actuating bars 35. The lug 58 upon the flange 57 limits the downward movement of the outer free end of the lever 59, while the spring 60 normally holds the inner end thereof carrying the disk engaging felt roller 61 upward and out of the path to be engaged by the bar 42 when the shaft 19 is elevated as will presently appear.

The forward end 62 of the lever 59 is disposed in the path to be engaged by the lug or block 63 connected to and projecting from the rear face of the bar 35, so that when the key 41 is actuated, and the bar 35 elevated, the lever 59 will be operated so as to depress its felt roller 61, but as the shaft 19 has not been elevated, the lever 59 will not be vibrated to produce the desired quaver effect upon the bowing disk. Simultaneously with the actuation of the key 41, the soft end 65 of the pin 64 will engage the damper lever 66. This action will move the damper 69 from engagement with the string C, said lever 66 being mounted in its bracket 67 and being automatically returned to string engagement by the spring 68.

In order to normally maintain the shaft 19 in such a position that the bar 42 will not be moved in engagement with the respective felt rollers 51 and 61, the lever 70 is pivoted to each plate 21. This lever is provided with the recess 71 and due to its spring 72, said lever has its recess 71 placed astride the shaft 19, as particularly illustrated in Fig. 5. The spring 72 is of such strength, however, as to permit of the proper lowering and elevating of the shaft 19 when it is desired to actuate the quaver lever 59 or the tremolo hammer 48.

Two levers 73, which are pivoted to the respective plates 21, are connected to the journals of the shaft 19 so that said shaft 19 may be lowered or elevated when desired. A spring 74 normally holds the lever 73 in the position as shown in Figs. 3 and 5. In order to lower the shaft so as to bring the bar 42 into engagement with the selected elevated tremolo actuating roller 51, the actuating rod 76 provided with the adjusting turn buckle 77 is connected to the notched end 75 of the lever 73 and as clearly shown in Fig. 6, is connected to the crank arm 86 of the

rock shaft 87. The forward end of the rock shaft 87 is connected to the longitudinally slidable bar 88 disposed in the front portion below the key board of the piano, for actuation by the knee actuated lever 91, when the same is moved to the left as viewed in Figs. 1 and 6. Thus the lug 90 connected to and carried by the bar 88 will be engaged by the lever 91 and the bar 88 will be moved and thus cause the two shafts 87 to be rocked and depress the two vertical rods 76 and levers 73 which cause the shaft 19 to be lowered to bring the disk 42 in engagement with the roller 51.

In order that the shaft 19 may be elevated so that the bar 42 will be placed in engagement with the roller 61 of the quaver actuating lever 59, and thus produce the necessary quaver effect upon the selected bar 35, and consequently its selected bowing disk, the link 78, carried by each lever 73 is pivotally connected to a double lever 79. This lever 79 is pivoted intermediate of its ends to its supporting plate 21, and has its notched free end 81 connected to the operating rod 82. The rod 82 is provided with an adjustable turn-buckle 83, as clearly illustrated in Fig. 3, and has its lower end operably connected to the rock shaft 84, there being two of these shafts, each one of which is connected to the forward sliding bar 85, as clearly illustrated in Fig. 6, so that when the knee lever 91 is moved to the right as viewed in Figs. 1 and 6, the lever 91 will engage a lug 89 carried by the slidable bar 85 and thus move the bar 85 to the right. Consequently the shaft 19 is caused to be elevated and carry with it its bar 42, and as the selected key bar 35 has been depressed, the roller 61 of the selected lever 59 will be placed in engagement with the rapidly rotating bar 42 so that the lever 59 will have imparted thereto a vibration which in turn will vibrate the selected bar 35, and bow flexing rod 30. The bar or lever 91 is provided with a knee engaging member 92 disposed in ready access to the operator.

Resin applying device.—In order that the string engaging edges 26 of the respective bowing disks may have properly applied thereto the necessary resin, a vertically swinging longitudinally disposed plate 93 is hinged for longitudinal sliding movement and also vertical swinging movement by means of a plurality of hinge members 94, carried by the plates 93, and 95 carried upon the upper face of the plate 29. The free edge 96 of the plate 93 is slightly offset and has connected thereto, one to each bowing disk 25, a resin holder 97, which carries the block 98 of resin. This block 98 of resin, disposed adjacent to its bowing disk, is normally out of contact therewith. Carried upon the under face of the plate 93 are a plurality of casters 99, which engage the 130

upper surface of the plate 29 and thus anti-frictionally support the free end of the plate 93 when the same is moved longitudinally into and out of resin-supplying position.

- 5 In order to resiliently oppose the upward movement of the plate 93 due to the rotation of the bowing disk 25 when in engagement with the resin block 98, a plurality of hinge plates 100 are connected to the plate 29 and 10 carry the yokes 101, each one of which is provided with a soft caster or roller 102 held by means of the spring 103 into resilient engagement with the upper face of the plate 93 as clearly illustrated in Figs. 7, 8 and 9.
- 15 In order to longitudinally move the plate 93, so as to place the blocks of resin 98 into engagement with all of the bowing disks simultaneously, the link 105 is pivotally connected to the pin 104, as clearly illustrated 20 in Fig. 6, and is operated by the crank arm 106 of the vertical shaft 107, said vertical shaft 107 being controlled finally through the bar 108, which is disposed in ready access to the player. Carried upon the vertical shaft 107 is the spring 109, which normally operates the rod 107 to return the plate 93 and the blocks of resin 98 out of engagement with the bowing disks.

- 30 *Damper actuating device.*—In order to produce the desired sustained tones in the strings C, the damper 69 should be moved from engagement with the strings C, and in order to accomplish this, the structure particularly shown in Figs. 6 and 14 is employed. The damper lever actuating plate 110 is pivoted to the rear face of the plate 35 39 by means of the pivoting lugs 111, said plate 110 being provided with a plurality of operating arms 112, each of which is operably connected through its respective links 113—113', to a bell crank lever 114, and a crank arm 115. The lever 114 and crank 115 are keyed upon the respective ends of the shaft 116. The bell crank lever 40 45 114 is the operating lever for the shaft 116, and is connected through the link 117 to a bell crank lever 118 mounted at the forward under portion of the piano cabinet, said bell crank lever 118 being operably connected through the rod 119, to the knee actuated lever 120, so that as the knee-engaging portion 121 thereof is moved to the left, as viewed in Figs. 1 and 6, the rod 119 is operated to cause the plate 110 to move all of 50 55 the dampers 69 from engagement with the strings.

In order to limit the depression of the keys and thus limit the movement of the bars 35, a hooked rod 122 is disposed to be engaged by the knee actuated lever 120 when the same is moved to the right, as viewed in Figs. 1 and 6, and through the lever 123, moves the key limiting bar 124 so that the cam slots 125 will ride past and 60 65 out of the cams 126 carried by the piano

frame below the key board in any desired manner, the cams 126 thus elevating the bar 124 throughout its length so that a key limiting and abutting means is disposed throughout the key board below the keys, 70 and so that as such keys are depressed, the distance of depression will be limited by the bar 124.

From the foregoing description, taken in connection with the drawings, it is evident that the structure shown in the before mentioned patent, is greatly simplified by the present structure, the shaft 19 being controlled to produce the quaver and also the tremolo effect without the necessity of 75 mounting the bowing disks so that the said bowing disks are moved to and from the strings, as is the case in the before mentioned patent. The bowing disks in the present instance are maintained in the same 80 position relatively to the strings and each is simply flexed by means of the crank of the rock shaft 30, through the key actuated bar 35 to produce the necessary movement of the bowing disk toward its string.

In order to provide a means whereby the present device may be operated through a piano-playing mechanism, upon the forward face of each bar 35, as clearly illustrated in Fig. 12, is mounted a lug 130, the same being provided with an elongated slot 131 for the reception of the adjusting and fastening screw 132, said slot permitting the adjustment of the lug 130, so that the same may be moved to any position to either be 90 engaged by the arm 133 actuated by a piano player mechanism (not shown) or out of the path thereof so that the keys 41 may be manipulated manually, as in an ordinary piano.

What is claimed is:

1. A violin piano, having a prime mover, a string, a shaft rotated from the prime mover, a flexible bowing disk rotatable with the shaft, a key, a bar operable from the key, means for flexing the disk operably connected to the bar, a second shaft rotated from the prime mover and mechanism actuated by the second shaft for imparting vibratory movement to the bar to intermittently flex the bowing disk during the depression of the key.

2. A violin piano, having a prime mover, a string, a shaft rotated from the prime mover, a flexible bowing disk rotatable with the shaft, a key, a key-actuated bar, means for flexing the disk operably connected to the bar, a second shaft rotated from the prime mover, mechanism actuated by the second shaft for imparting vibratory movement to the bar to intermittently flex the bowing disk during the depression of the key, said mechanism including a corrugated bar carried by and rotatable with the second shaft, a projection carried by the key 105 110 115 120 125 130

- actuated bar, and means disposed in the path to be engaged by both the corrugated bar and the projection for causing the bar to actuate the key-actuated bar.
- 5 3. A violin piano, having a prime mover, a string, a shaft rotated from the prime mover, a flexible bowing disk rotatable with the shaft, a key, a bar operably connected to the key, means for flexing the disk operably connected to the bar, a second rotatable shaft operably connected to the prime mover, a corrugated bar keyed upon and rotatable with the second shaft, and a lever pivoted intermediate of its ends and having 10 one end disposed to be placed in engagement with the corrugated bar while the other end is disposed in the path to be engaged by the key bar when the key bar is elevated due to the depression of a key, the rotative action imparted to the corrugated bar when the lever is in engagement therewith imparting through the lever a vibratory action to the key bar and bowing disk.
4. A violin piano, having a prime mover, 25 a string, a shaft rotated from the prime mover, a flexible bowing disk rotatable with the shaft, a key, a bar operably connected to the key, means for flexing the disk operably connected to the bar, a second rotatable shaft operably connected to the prime mover, said second shaft being mounted for oscillatory movement, means for oscillating the second shaft, a corrugated bar keyed upon and rotatable with the second shaft, and a 30 lever operably connected to a key bar and mounted for engagement with the corrugated bar to impart a vibratory movement to the key bar when the key is depressed and the corrugated bar is moved to engage the 40 lever and is rotated.
5. A violin piano, having a prime mover, a plurality of strings, a frame mounted in front of the strings, a longitudinally disposed shaft journaled for rotation in said 45 frame and operably connected to the prime mover, a plurality of bowing disks one to each string keyed upon and rotatable with the shaft, means for flexing each bowing disk to place the same in engagement with its string, a plurality of vertically movable 50 key actuated bars, one to each of said last means operably connected thereto, a plurality of keys, one key being connected to each key actuated bar, a second shaft rotatably mounted in the frame, means carried by the frame and connected to the shaft for bodily oscillating the shaft relatively to the frame, a corrugated bar keyed upon and rotatable with the second shaft, a lever to 55 each key actuated bar disposed in the path thereof and operated thereby during the depression of a key and the elevation of a key actuated bar, and means mounted in one
- end of the lever for engagement with the corrugated bar, whereby when the key-actuated bar is elevated, the selected bowing disk will be vibrated due to the engagement of the corrugated bar with the lever.
6. A violin piano, having a string, a rotatable shaft, a bowing disk loosely mounted thereupon for limited longitudinal movement, said bowing disk being rotatable with the shaft, and means mounted upon the shaft for limiting the longitudinal movement of the bowing disk.
7. A violin piano, having a string, a rotatable shaft, a bowing disk loosely mounted thereupon for limited longitudinal movement, said bowing disk being rotatable with the shaft, and means mounted upon the shaft for limiting the longitudinal movement of the bowing disk, said bowing disk being composed of a plurality of nested concaved disks.
8. A violin piano, having a string, a rotatable shaft, a bowing disk loosely mounted thereupon for limited longitudinal movement, said bowing disk being rotatable with the shaft, and means mounted upon the shaft for limiting the longitudinal movement of the bowing disks, said bowing disks being composed of a plurality of flexible concaved disks to provide a plurality of concentrically disposed string engaging edges.
9. A violin piano, having a plurality of rotatable bowing disks, means for supplying resin to said disks, including a support, a plate hingedly connected to said support for longitudinal and vertical movement, a plurality of resin holders one to each bowing disk carried by said plate, and manually-operable spring-returned means for sliding the plate to move the resin holders into resin-supplying position relatively to the bowing disks.
10. A violin piano, having a plurality of rotatable bowing disks, means for supplying resin to said disks, including a support, a plate hingedly connected to said support for vertical and longitudinal movement, a plurality of resin holders one to each bowing disk carried by said plate, manually-operable spring-returned means for sliding the plate to move the resin holders into resin-supplying position to the bowing disks, and resilient means for limiting the vertical movement of the plate during the supplying of resin to the disks.

In testimony that I claim the foregoing as my own, I have hereto affixed my signature in the presence of two witnesses.

ERICK SILEN.
